Inventor

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

METHOD OF PRODUCING IMPROVED COLOR EFFECTS IN TWO-PLY INGRAIN CARPETS.

SPECIFICATION forming part of Letters Patent No. 371,571, dated October 18, 1887.

Application filed May 13, 1887. Serial No. 238,043. (Specimens.)

To all whom it may concern:

Be it known that I, JAMES L. FOLSOM, of Brooklyn, New York, have invented a certain new and useful Method for Producing Improved Color Effects in Two-Ply Ingrain Carpeting, of which the following is a full, clear, and exact description, reference being had to the accompanying drawings, and to the letters and figures of reference marked thereon, which form a part of this specification.

My invention relates to a method of weaving two ply ingrain carpets, by which the filling threads of the two plies are so disposed and arranged as to produce improved and novel color effects and designs.

Hitherto in weaving two ply ingrain carpets, where there were two or more differently-colored filling-threads in a ply, the threads of that ply have been shot successively with respect to each other—that is, a thread of one color, then a thread of the second color, then a thread of the third color, and so on until a thread of each color had been shot, and then the same order would be repeated. For example, in weaving the most common form of two-ply ingrain carpets—namely, that having two filling-threads of different colors in each ply—a thread of one ply was thrown, then a thread of the other ply, then the second thread of the first ply, and, lastly, the remaining thread of the second ply, and then this succession of threads was repeated. Thus the order and arrangement of the colors upon the surface of the carpet were necessarily limited.

In my improved method I employ two filling-threads in the figure ply and three filling-threads in the ground ply. These filling-threads I throw in a regular but novel succession. For example, if the two threads of the figure ply are red and black, I throw them in the following order: red, black, black, black, red, black, black, black, and so on, throwing the second filling-thread three times to each single throw of the first filling-thread. If the three filling-threads of the ground ply are white, cinnamon, and blue, I throw them in a definite order—as, for example, white, cinnamon, blue, cinnamon, white, cinnamon, blue, cinnamon, and so on. As the loom throws a shot in each ply alternately, the actual order

of the filling-shots in the weaving of the carpet would be as follows: *red*, white, *black*, cinnamon, *black*, blue, *black*, cinnamon, *red*, white, *black*, cinnamon, *black*, blue, *black*, cinnamon, and so on, the colors in italics representing the threads of one ply and those not in italics the threads of the other ply. Figure 1 is a diagram representing a longitudinal section of the carpet woven in this manner, so far as to show the relative positions of the different filling-threads, it being assumed, for the sake of greater clearness, that all the threads of the figure ply are up and all the threads of the ground ply are down. In this diagram 1 is a section of a red filling thread; 2, white; 3, ⁵⁵ black; 4, cinnamon; 5, black; 6, blue; 7, black; 8, cinnamon; 9, red; 10, white; 11, black; 12, cinnamon; 13, black; 14, blue; 15, black; 16, cinnamon. This arrangement would be repeated.

By means of the jacquard the thread of either ply can be thrown up to the top of the carpet, the corresponding thread of the other ply being ordinarily thrown down to the bottom at that point of the fabric. The filling-threads ⁷⁰ employed in the two plies may of course be of any colors desired so long as three colors are employed in one ply and two colors in the other ply; but the filling-threads must be shot and woven into the carpet in a defined succession, as is indicated above. The particular succession or arrangement of the filling-threads on the surface of the carpet will be greatly varied by the operation of the jacquard, which can be made to throw the threads of either ⁷⁵ 80 ply to the top of the fabric at any point, as desired.

The characteristic feature of my invention lies in the employment of the different numbers of filling-threads in the two plies—two in one ply and three in the other ply—and in the special order of succession of those threads—viz., in one ply one shot of one thread, followed by three shots of the other thread, and in the other ply one shot of each thread at a time, ⁹⁰ 95 the threads succeeding each other in any defined order. As a result of my improved process, I produce novel and superior color effects on the face of two-ply ingrain carpets different from anything hitherto produced.

My invention may be carried out in any loom adapted to weave two-ply ingrain carpets by providing the proper number of shuttles and shuttle-boxes both for the forward 5 and rear shuttle frames of the loom and mechanism to bring those shuttle-boxes in proper succession into operative position for their shuttles to be acted upon by the picker-sticks. For instance, Figs. 2 and 3 show the changes 10 which it is necessary to make in a two-ply ingrain loom in which the path of motion of the picker-stick on either side of the loom is always the same and the shuttle-frame is moved so as to bring the shuttles, when desired, within 15 the range of motion of the picker-stick. Fig. 2 is a side view of the rear shuttle-frame of such a loom on one side of the loom and of its operating and controlling mechanism, and Fig. 3 is a similar view of the front shuttle-frame. In both of these figures G is the shuttle-box frame and supporting-rod. C is a lever fulcrumed in the frame of the loom at E, and carrying the shuttle-box frame G at its end F, where it is pivoted to such frame, and 20 held down at its end L by the strong spring M, secured to a part of the loom-frame N. This lever C is held down at its end L, so that the roller D, mounted on it, is kept always in contact with the cam B in the one 25 case and with the cam B' in the other case, which are mounted on the cam-shaft A of the loom. These two shuttle-regulating mechanisms represented in Figs. 2 and 3 are distinct from each other in the loom, excepting 30 that the cams B and B' are both mounted on the same cam-shaft, A, and the two shuttle-box frames G (to wit, the front and rear shuttle-box frames) are adapted in any well-known way to be alternately presented to the picker-stick, whose position is indicated at P in 35 both figures.

In Fig. 2, S and R are the two rear shuttle-boxes, adapted to receive shuttles carrying, respectively, say, black and red yarn, S in the

instance assumed above receiving a shuttle 45 carrying black yarn and R a shuttle carrying red yarn. The shape of the cam as shown in Fig. 2 presents the shuttle-boxes S and R in a definite succession—to wit, S S R S S S R S—to the picker-stick, the position of which 50 is indicated at P, and thereby determines the order of succession of the shots of filling-thread in the ply under consideration—to wit, the figure ply—as assumed above.

In Fig. 3, H, J, and K are the three shuttle-boxes adapted to receive shuttles carrying, say, blue, cinnamon, and white, respectively, H in the instance assumed above receiving a shuttle carrying blue yarn, J a shuttle carrying cinnamon yarn, and K a shuttle carrying 60 white yarn. The shape of the cam as shown in Fig. 3 presents the shuttle-boxes H, J, and K in a definite succession—to wit, H J K J H J K, &c.—to the picker-stick at P, and thereby determines the order of succession of 65 the shots of filling-thread in the ply under consideration—to wit, the ground ply.

I do not herein claim the mechanism herein described, nor do I restrict myself to any particular mechanism.

What I claim as new, and desire to secure by Letters Patent, is—

The method, substantially as described, of producing improved color effects in two-ply ingrain carpets, which consists in employing 75 two distinct and differently colored or shaded filling-yarns for one ply, throwing such filling-yarns in such ply in the definite order or succession of one throw of one yarn and three throws of the other yarn, and employing three 80 distinct and differently colored or shaded filling-yarns for the other ply, and throwing such filling-yarns in such second ply in any definite order or succession.

JAS. L. FOLSOM.
